SPINDLE OF YARN SPINNING MACHINES

Richard G. Peeples, Atlanta, Ga.

Application May 17, 1949, Serial No. 93,669

4 Claims. (Cl. 308—155)

1

My invention relates to improvements in spindles of yarn spinning machines.

An important object of the invention is to provide a spindle having a novel sediment chamber or sludge trap, wherein any sediment or sludge present in the lubricating oil for the spindle may settle out, and the spindle will thus be prevented from binding during its operation.

A further object is to provide a lubricant sediment chamber or sludge trap for spindles, which can be made either as an attachment for presently existing standard types of spindles, or readily incorporated in the manufacture of new spindles.

A further object is to provide a sludge trap attachment which may be applied to presently existing spindles with minimum alteration of such spindles, the sludge trap being extremely simple and very inexpensive to make.

A still further object of the invention is to provide a sludge trap or sediment chamber to be mounted upon the spindle base without substantially increasing the diameter of the base, thus permitting the use of the standard nut generally employed to detachably secure the spindle to the spindle rail.

Other objects and advantages of the invention will be apparent during the course of the following description.

In the accompanying drawings, forming a part of this application, and in which like numerals are employed to designate like parts throughout the same,

Figure 1 is a side elevation of a spindle embodying my invention and having a sludge trap mounted thereon.

Figure 2 is an enlarged central vertical longitudinal section through the spindle, parts in elevation, part broken away.

Figure 3 is a similar section taken on line 3—3 of Fig 2.

Figure 4 is a horizontal section taken on line 4—4 of Figure 2.

Figure 5 is a similar section taken on line 5—5 of Figure 2.

Figure 6 is a similar section taken on line 6—6 of Figure 3, and

Figure 7 is a central vertical longitudinal section through a bolster, removed, and associated elements.

In the drawings, where for the purpose of illustration is shown a preferred embodiment of my invention, the numeral 10 designates a conventionally spindle rail of a spinning machine, and provided with a plurality of openings 11 to receive a plurality of spindles, each such opening

2

and spindle being shown in the drawing. The spindle shown comprises the usual spindle base including an integral upstanding cylindrical tubular extension or sleeve 13, having its top open, and formed with a conventional oil neck 14 having an oil passage 15 as shown. The oil neck is provided with a conventional hinged cap 16. The spindle base 12 further comprises an integral depending cylindrical tubular stem or sleeve 17, having an upper smooth portion 18 for engagement within the opening 11, the spindle base having an enlarged flat annular shoulder 19, integral therewith, at the top of the sleeve 17, and adapted to engage upon the top of the rail 10 for supporting the spindle. The spindle base has a central longitudinal bore 20 of uniform diameter extending from the top of extension 13 to a point near the bottom of the sleeve 17. The sleeve 17 includes a bottom end 21 having a central longitudinal opening 22, and also a plurality of circumferentially spaced relatively small drain openings 23 surrounding the central opening 22, as shown, and leading from the bore 20. Below the smooth portion 18 and below the spindle rail 10, the sleeve 17 is provided with external screw threads 24, for receiving a nut 25 and washer 26, which elements serve to detachably secure the spindle to the rail 10. Below the screw threads 24 the sleeve 17 has its diameter 30 reduced for forming a reduced smooth cylindrical portion 27 of uniform diameter. The oil passage 15 leads into the bore 20 as shown.

Mounted within the bore 20 of the spindle base 12 is the usual tubular bearing or bolster 28, including an upper smooth cylindrical portion 29 having a close fit within the upper end of the bore 20, and provided with a radial longitudinal key 30 to engage in a longitudinal key-way 31, formed in the upper end of the bore 20. The key 30 prevents rotation of the bolster 28. In the upper portion 29 of the bolster, it is provided with diametrically oppositely disposed external longitudinal grooves 32, and a plurality of longitudinally spaced openings, or ports 33 are provided leading from the bore 34 of the bolster into the grooves 32. Below the portion 29 of the bolster, its outside diameter is reduced for producing an annular space 35 between the bolster and sleeve 17 below the oil passage 15, as shown; and near and above the lower end of the bolster, it is provided in its side with diametrically oppositely disposed longitudinal slots 36, for a purpose to be described. The bottom of the bore 34 is countersunk to provide a central conical seat 37 or thrust bearing 37 for the spindle, and the

bolster further includes a solid bottom extension 38, conically tapered at its lowermost end 39. The extension 38 is provided with a plurality of external longitudinal shallow grooves 40, a diametrically oppositely arranged pair of which lead into the bottom ends of the slots 36, Figure 7. The lowermost end of the bolster 28 rests upon the lower end 21 of the spindle base, as shown, and is spaced radially inwardly of the drain openings 23, so that these openings are uncovered and in communication with the annular space 35 at all times, Figure 3. The lower end of the bolster covers the central opening 22, as shown, but the grooves 40 place the opening 22 in communication with the annular space 35. Figures 2 and 7.

The numeral 41 designates a conventional spindle, having the usual acorn 42 formed thereon, and carrying the usual whorl 43; the whorl engaging over the upper end of the extension 13 as shown in Figures 2 and 3. The spindle includes an integral lower shank 44, which extends into the bore 34 of the bolster and has a close smooth running fit therein. The lower portion 44' of the shank 44 tapers slightly and is provided with a pointed conical lower end 45 rotatably engaging in the conical seat 37.

A trap for sludge and sediment is provided in the form of a thin walled straight cylindrical tube 46, which is preferably expanded by heat and applied to the lower portion 21 of the sleeve 17, and then allowed to cool so that it will have a tight shrink fit upon the sleeve. The upper end of the tube 46 abuts a narrow shoulder 46' at the lower end of the screw threads 24, as shown, and the tube 46 extends below the bottom end 21 of the spindle base for a substantial distance to form a sludge receiving chamber 47. In its lowermost end, the tube 46 is provided with an internally screw threaded bushing 48, rigidly secured therein, and receiving a removable screw threaded drain plug 49. The outside diameter of the tube 46 is uniform and slightly less than the inside diameters of the nut 25 and washer 26, so that the standard nut and washer may be readily applied over the tube 46.

In operation, oil is supplied through the passage 15 of the neck 14, and such oil enters the annular space 35 between the bolster and sleeve 17. This oil will pass through the openings 23 at the bottom of the space 35, and fill up the chamber 47 as well as the entire space 35, up to the level of the neck passage 15. The spindle 41 rotates at high speed, as is well known, and its lower shank 44 rotates within the bolster 28. Oil enters the bolster through the slots 36, which are adjacent to the lower tapered portion 44' of the shank 44. This oil will slowly work its way up between the bolster bore 34 and shank 44 to thoroughly lubricate the spindle shank, and some of the oil will pass out through the radial ports 33 at the top of the bolster, and then pass downwardly through the longitudinal slots 32, returning to the annular passage 35. In this manner the oil continuously circulates slowly about the shank 44 during its rotation.

Due to the presence of water from the humidifier system and lint in the air of the spinning room, and other factors, the lubricating oil may contain some solid particles of foreign matter apt to form a sludge or paste with the oil, which may tend to bind the spindle shank 44 and cause damage. The tube 46 forming the sludge receiving chamber 47 is designed to prevent this by permitting gradual settling of the solid matter or

sludge through the drain openings 23 and 22 into the chamber 47. The grooves 40 permit the passage of some sludge through the central opening 22, which opening would be normally covered by the lowermost end of the bolster in a conventional spindle. In some spindle bases, due to their design, it is not practical to form the surrounding drain openings 23. In that case, the grooves 40 are provided and will permit the sludge to settle into the chamber 47, through the central opening 22. I also contemplate omitting entirely the grooves 40 and relying upon the drain openings 23. Since the chamber 47 is below the stationary end 21 of the spindle base, and entirely remote from any turbulence due to the rapid rotation of the spindle, there is no tendency for the sludge which settles in the chamber 47 to be stirred up and recirculated upwardly into the annular passage 35 or into the bolster. During the circulation of the oil between the spindle base, bolster, and spindle, the solid matter or sludge will settle into the trap or chamber 47, as stated. The sludge in the chamber 47 may be cleaned out by removing the drain plug 49. It is obvious that the tube 46 forming the sludge trap can be readily applied to existing conventional spindles in the field, or it can be supplied with new spindles during their manufacture.

It is to be understood that the form of the invention herewith shown and described is to be taken as a preferred example of the same and that various changes in the shape, size, and arrangement of parts may be resorted to without departing from the spirit of the invention or the scope of the subjoined claims.

Having thus described the invention, I claim:

1. In a spindle mounting, a tubular spindle base having a flange near its upper end and a screw threaded portion spaced axially from the flange and arranged beneath the same, said spindle base having a lower reduced portion extending axially beyond the screw threaded portion, said lower reduced portion having opening means in its lower end, a tubular bolster disposed within the tubular spindle base and having a lower reduced portion, said tubular bolster being provided near its upper and lower ends with openings, a rotatable spindle having a shank mounted within the tubular bolster, a tube mounted upon the reduced lower portion of the spindle base and having a contact fit therewith, the outside diameter of the tube being less than the inside diameter of the screw thread of the screw-threaded portion, the tube extending below the tubular bolster for a substantial distance for forming a sludge trap, and a nut to engage with the screw threaded portion of the spindle base, said nut having an inside diameter greater than the outside diameter of the tube.

2. In a spindle mounting, a tubular spindle base having a flange near its upper end and a screw threaded portion spaced axially from the flange and arranged beneath the same, said spindle base having a lower reduced portion extending axially beyond the screw threaded portion, said lower reduced portion having opening means in its lower end, a tubular bolster disposed within the tubular spindle base and having a lower reduced portion, said tubular bolster being provided near its upper and lower ends with openings, a rotatable spindle having a shank mounted within the tubular bolster, a tube mounted upon the reduced lower portion of the spindle base and having a clamping contact fit therewith, the outside diameter of the tube be-

ing less than the inside diameter of the screw threads of the screw-threaded portion, the tube extending below the tubular bolster for a substantial distance for forming a sludge trap, a removable element connected with the lower end of the tube so that the sludge trap may be drained, and a nut to engage the screw threaded portion of the spindle base, said nut having an inside diameter greater than the outside diameter of the tube.

3. In a spindle mounting, a tubular spindle base provided in its lower end with a central opening, a tubular bolster disposed within the tubular spindle base and having a lower reduced portion, said tubular bolster being provided near its upper and lower ends with openings, the lower end of the tubular bolster covering the central opening and the tubular bolster being provided upon its periphery and near its lower end with longitudinal grooves which lead into the central opening, a tube mounted upon the lower portion of the spindle base and extending below the tubular bolster for forming a sludge trap.

4. In a spindle mounting, a tubular spindle base having a bottom, said bottom having a group of

openings arranged near the side of the tubular spindle base, a tubular bolster disposed within the tubular spindle base and having a lower reduced end to contact with the bottom of the tubular spindle base, said tubular bolster being provided near its upper and lower ends with openings, a rotatable spindle having a shank mounted within the tubular bolster, and a tube mounted upon the lower portion of the spindle base and extending below the tubular bolster for forming a sludge trap.
